UNITED STATES PATENT OFFICE.

ROLAND S. KELSEY, OF SYRACUSE, NEW YORK.

SAFETY ATTACHMENT FOR VAPOR-BURNERS.

SPECIFICATION forming part of Letters Patent No. 295,651, dated March 25, 1884.

Application filed August 24, 1883. (No model.)

To all whom it may concern:

Be it known that I, ROLAND S. KELSEY, of Syracuse, in the county of Onondaga, in the State of New York, have invented new and 5 useful Improvements in Safety Attachments for Vapor-Burners, of which the following, taken in connection with the accompanying drawings, is a full, clear, and exact description.

10 The object of this invention is to render the manipulation of vapor-burners safer and more convenient to the user; and it consists in a novel construction and combination of certain safety devices applied to the burner, as 15 hereinafter fully described, and specifically set forth in the claims.

The invention is fully illustrated in the annexed drawings, wherein Figure 1 is a vertical transverse section of the safety apparatus 20 surrounding the burner. Fig. 2 is a detached plan view of the base of the burner. Fig. 3 is a horizontal section taken on line α α in Fig. 1, and Fig. 4 is a view illustrating the application of the burner to a cook-stove or 25 range.

Similar letters of reference indicate corresponding parts.

A represents a vapor-burner of any ordinary and well-known style and construction, 30 the fluid or gasoline being conducted to it by a pipe, P, which is connected with a suitable reservoir for the fluid, as illustrated in Fig. 4 of the drawings.

F denotes the usual needle-valve, which 35 controls the flow of the fluid to the burner, and a is the cup generally applied to the burner below the nozzle thereof for the purpose of collecting sufficient fluid to heat by its combustion the burner, and thereby generate from 40 the inflowing fluid the gas which escapes through the nozzle n and is ignited.

The burner A, I secure to a base, B, having an upward-projecting nipple, h, into which the stem e of the burner is screwed. The top 45 of the said nipple has an external shoulder, on which is seated the heating-cup a, before described. The base B is formed with a supplemental cup, b, which surrounds the nipple h and superincumbent cup a, and is thus

adapted to collect such fluid as may overflow 50 from the cup a. A discharge-pipe, c, taps the base of the supplemental cup b, and conducts the fluid from said cup to a suitable reservoir, R, located in any convenient and safe position, such reservoirs being generally arranged under the usual bottom shelf, T, of the range, as represented in Fig. 4 of the drawings. s denotes a screen, of fine wire-netting or finely-perforated metal sheet, spanning the top of the supplemental cup, and secured in 60 position by its inner edge interposed between the cup a and its supporting-shoulder on the upper end of the nipple h, and its outer edge seated in a circumferential rabbet, r, on the top edge of the interior of the cup b. This 65 screen serves to prevent the flame in the cup a from communicating with the gas which may arise from the reservoir R through the pipe c, and thus guards against explosions of the said reservoir. In the rabbet r, and upon the edge 70 of the screen s, is seated the annular base of a case, C, which rises above and surrounds the burner A, and is provided at the front with an opening, o, to afford the necessary access to the cup a for igniting the fluid contained therein when it is desired to light the burner. A cap or cone, D, is mounted on top 75 of the case C and provided with the usual vertical flame-conductor, E, directly over the nozzle n, and with a series of perforations 80 around its upper part for the distribution of the flame.

By means of the case C the flame from the cup a is confined around the burner, thus not only promoting the necessary heating of the 85 burner for generating the gas, but also rendering the ignition of the fluid in the cup a much safer to the operator.

Having described my invention, what I claim as new, and desire to secure by Letters Patent, 90 is—

1. The combination, with the burner and its heating-cup a, of a subjacent supplemental cup, a screen interposed between the two cups, and a discharge-pipe tapping the supplemental cup, substantially as and for the purpose 95 set forth.

2. In combination with the burner and its

cup *a*, the base *B*, provided with the cup *b*, the conduit *c*, tapping the cup *b*, and the screen *s*, interposed between the cup *a* and conduit *c*, substantially as set forth, and for the 5 purpose specified.

In testimony whereof I have hereunto signed my name and affixed my seal, in the presence

of two attesting witnesses, at Syracuse, in the county of Onondaga, in the State of New York, this 4th day of August, 1883.

ROLAND S. KELSEY. [L. S.]
